N-ACYLA MIDO FATTY ACID COMPOUNDS

Herman Plaut, Los Angeles, Calif.

Application January 9, 1951, Serial No. 205,119

13 Claims. (Cl. 260—404)

This invention relates to the preparation of new and useful polymerizable N-acylamido fatty acid compounds, and more particularly to such compounds in which the acyl group is either acryl or methacryl. This invention also relates to a new and inexpensive method for the preparation of these useful compounds.

It is an object of this invention to prepare compounds that are useful in the preparation of greases and soaps.

It is another object of this invention to produce such compounds as are susceptible to polymerization, thereby to increase the molecular weight of the compounds so that higher melting points and altered solubility are obtained. These properties are of particular usefulness in the preparation of greases, but are valued as well in the preparation of thickening agents and stabilizers.

It is also an object of this invention to prepare N-acylamido fatty acids cheaply by the use of inexpensive reagents and by simple procedures which can be carried out at or near room temperature and pressure, thereby permitting the employment of simple and inexpensive equipment.

The objects of the instant invention are realized by the reaction of an acrylo or methacrylo nitrile with an ethylenically unsaturated and unconjugated fatty acid, or a secondary hydroxy fatty acid wherein the secondary hydroxyl radical does not reside on the alpha carbon atom. The reaction is effected in the presence of a concentrated mineral acid, this term being used herein in the usual sense to mean such acids as sulfuric, phosphoric, boron trifluoride and similar acids. Isolation of the product is easily accomplished by drowning of the reaction mixture with water and filtering, extracting, or otherwise separating the product.

It has been discovered in accordance with the instant invention that the reaction outlined above takes place readily when use is made of fatty acids containing an ethylenically unsaturation or double bond, either at the end of the carbon chain—such as with undecylenic acid—or where the double bond occurs in the middle portion of the chain—such as with oleic acid; but the reaction does not occur where the unsaturation is conjugated with the carbonyl group—such as with acrylic acids. If a hydroxy fatty acid is used as the starting material, the hydroxy group must be located on a secondary carbon atom, since it has been found that the reaction with primary alcohol is too slow to be of practical value. The hydroxyl group can not reside on the alpha carbon atom, since it has been found that alpha-hydroxy-stearic acid and lactic acid are inoperative. However, beta-hydroxy acids, such as beta-hydroxy-caproic react readily.

Where an ethylenically unsaturated fatty acid is used as a reactant, there are generally obtained simultaneously a mixture of two products in varying proportions. When the unsaturation resides at the end of a carbon chain, only one product has been found—namely, the secondary derivative. Thus only 10-N-methacryl-amido-undecylenic acid is obtained from methacrylo-nitrile and undecylenic acid. In the case of the hydroxy fatty acids, the amino group enters the position previously occupied by the hydroxy group used in the starting material.

While mixtures of compounds are usually obtained when an ethylenically unsaturated fatty acid is used as a reactant, it has been found that such mixtures are not a disadvantage, but that they can be readily used together since the properties of the isomers are so similar. The isomers can be separated if desired by standard techniques such as chromatography.

2

The reaction desired herein is not limited in scope by the length of the fatty acid carbon chain. However, it has been found that fatty acids containing between 11 and 22 carbon atoms react to give products whose properties are especially desirable, and which products are within the scope of the instant invention.

It has been further found that the reaction is not limited to the fatty acids alone, but proceeds equally well with their derivatives. The presence of impurities in the starting materials, such as saturated fatty acids, in no way detracts from the effectiveness of the instant invention. Esters, amides, and mono and di-substituted amides react readily to give the acrylamido or methacrylamido compounds.

The use of a mineral acid which is concentrated is advantageous since it permits the reaction to be carried out at room temperature or below. This avoids the expense of heating and the necessity of utilizing equipment capable of withstanding high temperatures and pressures. Also, since the products are unsaturated compounds capable of polymerization under the influence of heat, especially in the presence of mineral acids, the use of low temperatures avoids the formation of such polymers and thus simplifies purification. Following purification of the product, the polymer may readily be formed therefrom if desired.

The manner of addition of the reagents is not critical. Any one can be added to a solution of the other two. However, the addition of the mineral acid to a solution of the organic reactants is preferred.

The acrylamido and methacrylamido fatty acids and derivatives thereof prepared herein can be polymerized to molecules of higher molecular weight by the use of high temperatures or the use of peroxide catalysts such as benzoyl peroxide. The products of such polymerization have properties useful in the production of alkyd resins, greases, stabilizers, and similar compounds.

The following examples are included herein in order to facilitate a more complete understanding of the instant invention. A number of variations in the process are included below in order to illustrate the scope of the invention disclosed.

Example 1.—A solution of 25 ml. of concentrated sulfuric acid was added slowly with stirring to 18.5 g. of undecylenic acid and 5.4 g. of acrylo nitrile in a 500 ml. 3-necked flask surrounded by an ice bath. The addition was regulated so that the temperature did not rise over 20° C., which required approximately one-half hour. The stirring was continued for two hours during which time the temperature was allowed to reach 40° C. The reaction mixture was then poured over 100 gms. of ice and the product extracted with 1000 ml. ether. The ether was washed with water, dried over anhydrous sodium sulfate and the product obtained by distillation of the ether. The residue was recrystallized from benzene to give white needles of 10-N-acrylamido-undecanoic acid, M. P. 104–105° C. Nitrogen analysis, calculated 5.48%, found 5.39%.

Example 2.—A solution of 18.5 g. of undecylenic acid and 6.7 g. of methacrylo nitrile was added slowly with stirring to 30 ml. of boron trifluoride etherate in a 500 ml. 3-necked flask surrounded by an ice bath. The addition was regulated so that the temperature did not rise over 20° C., which required approximately one-half hour. The stirring was continued for two hours during which time the temperature was allowed to reach 35° C. The reaction mixture was then poured over 100 gms. of ice. 1000 ml. ether was added. The ether was washed with water, dried over anhydrous sodium sulfate, and the product obtained by distillation of the ether. The residue was recrystallized from benzene to give white needles of 10-N-methacrylamido-undecanoic acid, M. P. 95–96° C. Nitrogen analysis: calculated 5.49%, found 5.41%.

Example 3.—To a solution of 5.4 g. of acrylo nitrile in 25 ml. of sulfuric acid was added slowly with stirring 28 gms. of oleic acid. The solution was cooled in an ice bath so that the temperature did not rise above 20° C. After the oleic acid had all been added, the reaction mixture was stirred for an additional two hours. The temperature was not allowed to rise above 40° C. The reaction mixture was poured onto ice and the solid material

washed well with water and the latter drained off. The product was melted, beaten with water, cooled, and the water drained off. The product, a mixture of 9-and 10-N-acrylamido-stearic acid, melts at 80-85° C. Nitrogen analysis: calculated 3.94%, found 4.01%.

Example 4.—A mixture of 31.6 g. of methyl 12-hydroxystearate and 5.4 g. of acrylo nitrile was added slowly with stirring to 25 cc. of concentrated sulfuric acid. The temperature was held below 25° C. by means of a water bath and allowed to rise to 50° C. after addition of the reactant. Stirring was maintained for two hours. The reaction mixture was poured onto ice and the product extracted with 500 ml. g. chloroform. The chloroform was washed with a dilute sodium bicarbonate solution and then with water. It was then dried over anhydrous sodium sulfate and the chloroform removed by distillation under slightly reduced pressure. The residue, methyl 12-N-acrylamidostearate, was a soft wax melting at 50-55° C.

Example 5.—A mixture of 26.1 g. of N-phenyl undecanoamide and 5.4 g. of acrylo nitrile was added slowly with stirring to 25 ml. of concentrated sulfuric acid maintained at 20° C. by an ice bath. After addition of the reactants, the reaction mixture was stirred for four hours holding the temperature below 30° C. The reaction mixture was poured onto ice and the solid material filtered off and washed with water. On recrystallizing from acetone, the N-acrylamido-N-phenyl undecanoamide melted at 148-151° C. Nitrogen analysis: calculated, 8.48%, found 8.67%.

Example 6.—A solution of 25.5 g. of 10-N-acrylaminoundecanoic acid and 14 g. of thionyl chloride was allowed to stand for several hours with occasional shaking. 27 gms. of the reaction mixture was added to a solution of 9.3 g. of aniline in 100 ml. of anhydrous pyridine. The reaction mixture was allowed to stand for twenty-four hours and then poured into an ice water mixture. The solid precipitate was filtered off and crystallized from acetone. M. P. 149-151° C. A mixed melting point with the 10-N-acrylamido-N'-phenylundecanoamide prepared in Example 5 gave no depression.

In addition to the compounds prepared in the above examples, the following compounds have been prepared by similar procedures:

Example	Compound	M. P.
7	10-N-acrylamidoundecanoamide	151-153° C.
8	Methyl 10-N-acrylamidoundecanoate	63-65° C.
9	Methyl 9 and 10-N-acrylamidostearate	40° C.
10	12-N-acrylamidostearic acid	60° C.
11	10-N-methacrylamidoundecanoic acid	95-96° C.
12	9 and 10-N-methacrylamidostearic acid	90-100° C.
13	Methyl 10-N-methacrylamidoundecanoic acid	65° C.
14	10-N-methacrylamidoundecanoamide	132° C.
15	10-N-methacryloamido-N'-phenylundecanoamide	132° C.
16	N-acrylamido fish oil fatty acid, containing fatty acids with 20 and 22 carbon atoms in the carbon chain	noncrystalline oil-sludge.
17	N-methacrylamido fish oil fatty acids containing fatty acids with 20 and 22 carbon atoms in the carbon chain	Do.

What is claimed is:

1. A mixture of 9-and 10-N-acrylamidostearic acid.
2. 9-N-acrylamidostearic acid.
3. 10-N-acrylamidostearic acid.
4. An N-acrylamidostearic acid wherein the nitrogen resides on a secondary carbon atom removed 7-10 (inclusive) carbon atoms from the carbonyl group.
5. An N-acrylamido acid compound wherein the acyl group is a member selected from the group consisting of: an acryl group and a methacryl group and the acid portion is a fatty acid substituent containing 11 to 18 (inclusive) carbon atoms, with the nitrogen

70

atom residing on a secondary carbon atom separated by 7 to 10 (inclusive) carbon atoms from the carbonyl group; and wherein the carbonyl group is joined to a member selected from the group consisting of (1) a hydroxyl group, (2) an alkoxy group, (3) an amino group.

6. The method of producing an N-acrylamidostearic acid compound which comprises reacting a hydroxystearic acid in which the hydroxyl group resides on a secondary carbon removed 7 to 10 (inclusive) carbon atoms from the carbonyl group with acrylo nitrile, in the presence of a strong mineral acid.

7. The method of producing an N-acyl amido acid compound which comprises reacting a fatty acid containing 11 to 18 carbon atoms and which forms carbonium ions in the presence of a strong mineral acid, with an acrylic nitrile of less than five carbons, in the presence of a strong mineral acid.

8. An acrylamido acid compound wherein the amino acid portion is a fatty acid substituent containing 11 to 18, inclusive, carbon atoms, with the nitrogen atom residing on a secondary carbon atom separated by 7 to 10 (inclusive) carbon atoms from the carbonyl group; and wherein the carbonyl group is joined to a member selected from the group consisting of (1) a hydroxyl group, (2) an alkoxy group, (3) an amino group.

9. An acrylamido acid compound of the formula:

30 wherein x may vary from 1 to 9, inclusive; y may vary from 7 to 15, inclusive; $x+y$ may vary from 9 to 16, inclusive; and R is a member selected from the group consisting of (1) a hydroxyl group, (2) an alkoxy group, (3) an amino group.

10. An acrylamido acid compound wherein the acid portion is a fatty acid substituent containing 11 to 18, inclusive, carbon atoms, with the nitrogen atom residing on a secondary carbon atom separated by 7 to 10 (inclusive) carbon atoms from the carbonyl group; and wherein the carbonyl group is joined to a hydroxyl group.

45 11. An acrylamido acid compound of the formula:

50 wherein x may vary from 1 to 9, inclusive; y may vary from 7 to 15, inclusive; $x+y$ may vary from 9 to 16, inclusive; and R is a hydroxyl group.

12. 10-N-acrylamidoundecanoic acid.

55 13. An N-acrylamido acid compound of the formula:

60 wherein x may vary from 1 to 9, inclusive, y may vary from 7 to 15, inclusive, $x+y$ may vary from 9 to 16, inclusive; R is a member selected from the group consisting of: a hydroxyl group, an alkoxy group, an amino group, and R' is a member selected from the group consisting of: hydrogen, a methyl group.
